SPECIALIZED BUILDING FOR VEHICLE SERVICE

Robert H. Young, P.O. Box 508,
Fond du Lac, Wis. 54935

Filed Mar. 25, 1968, Ser. No. 11,121

Term of patent 14 years

Int. Cl. D25—04

U.S. Cl. D13—1

FIG. 2 is a rear elevational view of the building shown in FIG. 1;

FIG. 3 is a fragmentary front elevational view of the building shown in FIG. 1; and

FIG. 4 is a fragmentary top plan view of the new design.

I claim:

The ornamental design for a specialized building for vehicle service, substantially as shown and described.
